METHOD OF CONSTRUCTING TANKS

Edwin B. Gates, Mertztown, Pa., assignor to The
Atlas Mineral Products Company, Mertztown,
Pa., a corporation of Pennsylvania

Application March 11, 1932, Serial No. 598,287

5 Claims. (Cl. 72—14)

This invention relates generally to an improved method of constructing tanks, and particularly tanks used in the pickling process of steel treatment.

Methods heretofore used in the construction of tanks of this character have not been entirely successful, as breaks occur at certain points in the bonding materials. The methods referred to usually include the laying of bricks or vitrified blocks with bonding materials including sulphur compounds, the practice being to lay successive courses of blocks, and to pour the bonding compound at the completion of each course. These alternate laying and bonding operations cause imperfect cohesion of the bonding materials, because of the fact that by the time the second pour is made the preceding pour has become cooled to such extent as to prevent a proper cohesion of the two bonds. In most instances delays occur in the completion of the entire tank, so that upon resumption of work, the hot materials will not properly cohere with the cold bond previously made. In instances such as these, uneven contractions and expansions occur, preventing proper bonding and usually resulting in breaks wherever such improper associations of materials have been made.

The present method contemplates the erection of tanks with materials identical with those heretofore employed, but in such manner as to retain a substantially constant temperature until the entire structure is complete.

The invention will be best understood by reference to the following detailed description and the accompanying drawing disclosing the improved process, and wherein:

Fig. 1 is a transverse sectional view taken through a base and wall erected in accordance with my improved process,

Fig. 2 is a top plan view,

Fig. 3 is an end view of the base and wall after the stripping process,

Fig. 4 is an enlarged side elevation of a part of the wall and showing the means for supporting the blocks or bricks, and ready for the pouring operation, and

Fig. 5 is a fragmentary vertical sectional view taken through a wall showing a slight modification.

Referring now more particularly to the drawing, 6 indicates a base or floor for the tank, which may be formed of vitrified blocks or bricks. A wall of the tank is indicated generally at 7, and it will be understood that this wall rests upon and extends entirely around the base or bottom

portion of the base 6. The wall 7 is provided with a bonding agent 8, which is applied to the base 6 and to the wall 7, so as to form a bonding element 9. The bonding element 9 is provided with a sheet 8 of paper or other thin material applied over the upper course of blocks, whereupon sand or insulating material 10 is positioned over the sheet 8. A substantially thick coating of insulating material is provided, in order to retain the heat within the base and to maintain a substantially constant temperature in the bonding agent.

In the erection of the walls, the lower course of bricks is laid and maintained properly spaced from each other upon the supporting foundation. The walls are laid between thicknesses 8 of sheet material, within a chamber provided between parallel upstanding forms 9 spaced a substantial distance beyond the sides of the wall blocks. A packing of insulating material 10 fills the spaces between the forms 9 and the next adjacent sheet 8, which insulating material may be sand, sawdust, cork or the like. Upon setting of the lower course of the wall, the hot bonding agent is poured, filling the spaces between the blocks and passing through to cohere with the hot bonding agent of the underlying base.

The courses of the walls are laid and poured successively, while the forms 9 and packing material are correspondingly erected. In other words, the leg of the wall progresses simultaneously with the up-building of the forms and the insertion of packing so that a substantial uniform wall temperature is retained throughout the height of the wall. In order to facilitate this operation, the forms will be made in sections.

In preparing a course of blocks for pouring, the several blocks of the course are laid upon chips 11 of bonding material as shown in Fig. 4, which, when the hot material is poured, will melt or dissolve and will cohere with the bonding agent. After the base and the several courses

have been laid in this manner until a proper height is reached, and upon the structure becoming cold or set, the same may be stripped of the forms and insulation as well as the sheets 8. The exterior surface of the wall may then be painted or treated if desired with a coat of the fluent bonding material as an added protection, or, if desired, the exterior surface of the walls may be enclosed with bands or a continuous sheet of metal indicated at 12 in Fig. 5. In instances where a continuous metallic plate is to cover the exterior surface of the wall, this plate will take the place of the exterior paper sheet 8. It will be understood that the sheets 8 prevent the hot bonding material coming in contact with the insulating material, as well as to properly define the mold within which the bricks or blocks are laid.

By erecting a structure in the manner described, it is apparent that a substantially even or constant wall temperature is obtained, as dissipation of the heat of the bonding material will be prevented by the insulation upon each of the wall sides. In erecting the tank in accordance with my method, it must be understood that completion of the work at one time is essential, as to allow the wall to become cold and then resume laying and pouring operations would defeat the objects of the invention. It has been found that by erecting tanks in the manner described, breaks or cracks in the bonding agent do not occur, and the objections common to the processes heretofore employed are entirely overcome.

Having thus described my invention, I claim:

1. The method of constructing a tank wall consisting of erecting spaced-apart heat insulated forms and laying a course of bodies between said forms, filling the interstices between said bodies by applying a bonding material while in a hot fluent condition, and repeating the foregoing steps until the wall is finished.

2. The method of constructing a wall consisting of erecting spaced-apart forms and arranging spaced-apart sheets of insulating material between said forms and in spaced parallel relation to each other and to said forms, filling the spaces between the sheets and the forms with a packing material, laying courses of blocks in spaced relation between said sheets and approximately simultaneously with the erection of the forms and sheets, and applying a hot bonding material to the spaces between said blocks.

3. The method of constructing a wall consisting in erecting relatively spaced heat insulating forms and at approximately the same time laying bodies between said forms, and binding said bodies by means of a bonding agent applied while in a hot fluent condition.

4. The method of constructing a tank wall consisting of positioning spaced-apart sheet-like insulating members and supporting them by forms and an intervening filling material, and laying bodies between said sheets in spaced relation to each other and in contact with the sheets, said bodies being laid at approximately the same time as the positioning of said sheets and their supports, and pouring a hot fluent bonding agent in the spaces between said bodies.

5. The method of constructing a tank consisting in forming a bottom by laying courses of blocks in spaced relation with respect to each other, covering the top of said bottom wall and the interstices between the blocks with heat insulation material, erecting spaced-apart heat insulating walls perpendicular with said foundation, laying blocks between the said perpendicular walls in spaced relation with each other and at approximately the same time as the erecting of said walls, and pouring a hot fluent bonding agent into the spaces between the blocks of said foundation and of said perpendicular wall.

EDWIN B. GATES.
